Patented Dec. 9, 1913.

UNITED STATES PATENT OFFICE.

HENRY H. WAIT, OF CHICAGO, ILLINOIS, ASSIGNOR, BY MESNE ASSIGNMENTS, TO
RATÉAU BATTU SMOOT COMPANY, A CORPORATION OF NEW YORK.

LAMINATED CORE FOR ELECTRIC GENERATORS AND MOTORS.

1,080,611.

Specification of Letters Patent.

Patented Dec. 9, 1913.

Application filed December 7, 1906. Serial No. 346,692.

To all whom it may concern:

Be it known that I, HENRY H. WAIT, citizen of the United States, residing at Chicago, in the county of Cook and State of Illinois, have invented a certain new and useful Improvement in Laminated Cores for Electric Generators and Motors, of which the following is a full, clear, concise, and exact description.

10 My invention relates to electric generators and motors, and has for its object to increase the efficiency and capacity of such machines by providing improved means for carrying away the heat generated in the cores thereof.

15 In the rotating field-magnet of an alternator, this heat comes almost entirely from the heating effect of the current flowing in the conductors; while in rotating armatures, it comes partly from the conductors and 20 partly from the hysteresis and eddy currents in the body of the core and in the teeth. It has been customary to accomplish the cooling of such cores by providing ventilating space in the interior communicating with 25 radial passages, whereby a circulation of air is caused when the core is rotated. In high-speed machines, such as those driven by steam turbines, the allowable peripheral speed limits the diameter of the rotor to a 30 small dimension, compared to its length and to the size of shaft required; and where the rotary member of such machines is an armature having a changing magnetic flux, the frequency of such change is very high, causing 35 a very great loss by hysteresis and eddy currents per unit of volume of the core. In such cases, it will be seen that not only are the possibilities for ventilation reduced, but the causes which necessitate provision for 40 carrying off the heat are increased.

The present invention offers a means for radiating the heat generated at the surface of the core either with or without the assistance of the usual ventilating passages.

45 Generally speaking, the invention consists in building up the core of laminations in such manner that at frequent intervals along the core, the edges of certain of the laminæ project beyond the edges of adjacent laminæ, 50 forming a large number of raised flanges or annular ribs which thus provide a greatly increased radiating surface for the core.

A feature of the invention consists in making such projecting laminæ or plates of non-magnetic metal of high heat-conductivity,

such as hard copper, bronze, or manganese steel, so that the increased radiating surface may be obtained without increasing the self-induction of the armature; and another feature consists in the projecting portions being 60 angularly inclined with reference to the direction of movement, so that they will act as fan blades to maintain a current of air along the core.

I will describe my invention more particularly by reference to the accompanying drawings, in which—

Figure 1 is a longitudinal sectional view of a dynamo armature, such as may be used for a high speed turbine-driven generator, 70 constructed in accordance with my invention; Fig. 2 is a detailed view taken cross-wise of the armature, showing one of the annular projecting copper plates surrounding and confining the electrical conductors 75 in the armature slots; Figs. 3 and 4 illustrate different groupings or dispositions of the projecting laminæ. Figs. 5 and 6 illustrate how the projecting portions of the teeth may be angularly inclined to serve as 80 fan blades; Fig. 7 is an enlarged detail view in longitudinal section illustrating the preferred form shown in Fig. 1 in which annular plates or laminæ of hard copper, interspersed at frequent intervals between the 85 iron laminations, and projecting beyond the outer surface of the core, extend only part way into the core, the central portions or disks within such annular copper plates being of iron to increase the magnetic conductivity in the interior of the core; Fig. 8 is a detail view of a modification showing a portion of the armature 4, in cross-section, looking at the face of one of the laminæ.

Like parts are designated by similar letters of reference throughout the several views.

The armature core shown in Fig. 1 is composed of iron disks or laminations *a* assembled upon a shaft *b*; heavy iron cheek plates being provided at the ends to hold the body of laminations together. As shown most clearly in Fig. 2, the periphery of the core may be slotted longitudinally, and the copper conductors *c c* of the armature winding 100 are embedded in these slots in the usual manner and suitably insulated; the terminals of the conductors being connected as usual to corresponding segments of the commutator *d*.

The laminations of the core are wholly or partly iron disks of different diameters disposed in such a way that the edges of certain laminæ a' at frequent intervals along the core, project radially beyond the edges of adjacent laminæ, forming a large number of annular flanges or ribs around the core and thereby greatly increasing the heat-radiating surface. These projecting laminæ a' may be arranged singly, as in Fig. 4, or in groups, as in Fig. 3. These projections revolve at a high peripheral speed, and consequently are very effective in dissipating the heat from the core. In Figs. 5 and 6, the projecting teeth are shown inclined to the direction of motion, so as to act as fan blades and maintain a draft of air longitudinally along the surface of the core.

In continuous current machines, the projecting teeth a' if of iron will add considerably to the self-induction of the windings. In machines having commutating poles, this increased self-induction may be compensated for, but in ordinary types of machines, it may be objectionable. This objection however, can be obviated by making the projecting disks of hard copper, bronze, manganese steel, or other non-magnetic metal which will be of high conductivity without contributing to the self-induction of the armature. In Figs. 1 and 7, the projecting laminæ a' are of such non-magnetic metal and extend only part way into the core, the space at the center, within each annular non-magnetic lamine, being occupied by a smaller concentric disk of iron. By such a construction, the magnetic conductivity of the armature as a whole is not seriously impaired, while the self-induction at the surface is kept low.

In commutating machines running at high speeds, where it is desired to avoid self induction, and yet have the slots closed at the top, the bronze disks can be made to surround the coils and serve to retain them, while the slots in the iron can be left wholly or partially open at the top. The conductors will be threaded through the holes in the bronze disks. Such preferred construction is indicated in Fig. 2.

While I have illustrated my invention as applied to a direct-current dynamo armature, it will be apparent that it is not limited to such application, but will be useful in the construction of the rotors of alternating-current machines; and may even be applied to the stator, in which case the circulation of air is caused by the windage from the rotor.

It will be noted that when a core constructed with circumferential heat-radiating ridges as above described is put into rotation relatively to the surrounding air, the heat dissipated by said ridges is carried off by

the passing air without stirring up wasteful eddy-currents in the air, as would be the case if projections were in any other direction than approximately parallel to the direction of relative rotation.

This invention is not to be confused with a construction of dynamo armatures previously devised by me, in which the tops of most of the teeth at the periphery of the armature are cut down to decrease the self-induction, leaving only a few teeth with ends overhanging the slot at two or three places along the length of the core to hold the conductors in place in the slot. In the present invention, which is for a widely different purpose, all the iron teeth are complete, and many of the laminæ at frequent intervals along the core project beyond the adjacent laminæ, forming a large number of heat radiating flanges or ribs, at the expense of deliberately increasing the self-induction, unless the projecting laminæ be made of non-magnetic material, as one form of my invention contemplates.

I claim:—

1. A core for electrical machines built up of iron laminations and plates of copper interspersed between said iron laminations, and a winding on said core, said copper plates projecting beyond the exterior surface of the core and its windings so as to form salient flanges adapted to dissipate heat.

2. A core for electric machines, built up of iron laminations, and plates of non-magnetic metal interspersed between said iron laminations, said core having slots receiving electric conductors, said non-magnetic plates extending over said slots to retain said conductors in place, and projecting beyond the iron laminations to form heat-radiating flanges.

3. A core for the rotors of electric generators and motors, built up of iron laminations, interspersed with annular non-magnetic laminations, projecting radially beyond the iron, but extending only part way into the body of the core, the inner space circumscribed by said annular non-magnetic laminations being filled by concentric disks of iron; whereby a large heat radiating surface is secured without unduly increasing the self-induction of the armature or impairing the magnetic conductivity of the core.

In witness whereof, I hereunto subscribe my name this 5th day of December A. D., 1906.

HENRY H. WAIT.
